UNITED STATES PATENT OFFICE.

CLYDE C. FARMER, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA.

ELECTRIC CONTACT DEVICE.

1,390,607.

Specification of Letters Patent. Patented Sept. 13, 1921.

Application filed December 10, 1919. Serial No. 343,950.

To all whom it may concern:

Be it known that I, CLYDE C. FARMER, a citizen of the United States, residing at Edgewood, in the county of Allegheny and State of Pennsylvania, have invented new and useful Improvements in Electric Contact Devices, of which the following is a specification.

This invention relates to electric contacts, 10 and more particularly to contacts for electric train wire couplings.

My invention has special reference to a contact adapted to make a butt contact with a corresponding contact and in which a relative movement of the contact faces is produced as the contacts engage, so that the engaging faces are maintained clean and bright.

An electric train wire coupling having contacts of the above character is disclosed in a prior Patent, No. 1,290,066, of T. R. Brown, dated January 7, 1919, and one object of my invention is to provide an improved contact of the above type.

Where there is relative movement of butt contacts as they engage, since the relative movement increases with the distance from the rotative center of the contact, it will be evident that the wear will be greater toward 30 the periphery of the contact than at the center, and consequently, in time, there may be sufficient wear, so that only the central portion of the contact will actually engage the corresponding contact, with the result 35 that the conductivity of the contact is reduced.

This wear also tends to prevent the rubbing action at the periphery of the contact which is necessary to maintain the contact 40 surface in the desired clean and bright condition.

Furthermore, particles of dirt tend to lodge at the central portion of the contact and thus prevent effective engagement of 45 the contacts.

Another object of my invention is to obviate the above difficulty by eliminating the bearing contact at the central portion of the contact.

50 In the accompanying drawing; Figure 1 is a sectional view of counterpart contacts for an electric train line coupling, in engagement, and embodying my invention; and Fig. 2 an end view of one of the contacts.

As shown in the drawing, the reference 55 numeral 1 represents the coupler head of a train line coupling and within said head are mounted one or more butt contact members 2.

The rear portion of each member 2 is provided with screw threads 3 of very coarse pitch adapted to engage corresponding grooves in a nut 4, the pitch being such that pressure applied to the contact face of the member will cause the same to rotate in the 65 nut 4.

A coil spring 5 acts through a collar 6 on the member 2 and tends to maintain said member extended, as shown in the drawing.

According to my invention, the central 70 portion of the meeting face of the contact member 2 is counter-bored out, as shown at 7, so that there will be no bearing contact at the central portion of the contact member.

As counterpart coupler heads are pressed 75 together in the act of coupling, the contact members 2 are forced rearwardly and rotate, through the engagement of the screw threads 3 in the grooves of the nut 4, and the meeting faces of corresponding contact members 80 2 rub on each other, so as to maintain the contact surfaces bright and clean.

Having now described my invention, what I claim as new, and desire to secure by Letters Patent, is:—

1. A butt contact member for an electric train line coupling having means for rotating the member upon engagement with a counterpart contact member and having a recess at the central portion of the contact 90 face removed.

2. In an electric train line coupling, the combination with a coupler head, of a butt contact member mounted in said head and adapted to be depressed by engagement with 95 a corresponding contact member in a counterpart coupler head and means operated by the coming together of said contact members for producing a relative rotative movement between the coacting faces of said contact members, the central portion of the meeting face of the contact member being cut away.

In testimony whereof I have hereunto set my hand.

CLYDE C. FARMER.

It is hereby certified that in Letters Patent No. 1,390,607, granted September 13, 1921, upon the application of Clyde C. Farmer, of Edgewood, Pennsylvania, for an improvement in "Electric Contact Devices," an error appears in the printed specification requiring correction as follows: Page 1, line 91, claim 1, strike out the word "removed"; and that the said Letters Patent should be read with this correction therein that the same may conform to the record of the case in the Patent Office.

Signed and sealed this 22d day of November, A. D., 1921.

[SEAL.]

WM. A. KINNAN,

Acting Commissioner of Patents.
